NECKTIE ROLLING AND PRESSING DEVICE

Frank O. Bergstrand, Worcester, Mass.

Application February 7, 1934, Serial No. 710,102

9 Claims. (Cl. 223—19)

This invention relates to a device for restoring freshness to neckties and ribbons after wearing, and for conveniently storing such ties or ribbons until again used.

- 5 It is the general object of my invention to provide an easily operated device by which a necktie or ribbon may be firmly pressed and rolled, thereby smoothing the article and removing wrinkles therefrom.
- 10 A further object is to provide a pressing and rolling device having provision by which a rolled tie or ribbon may be removed from the device and may be stored for any desired period, while the device itself is immediately available for further use.

15 My invention further relates to arrangements and combinations of parts which will be herein-after described and more particularly pointed out in the appended claims.

- 20 A preferred form of the invention is shown in the drawings, in which
- Fig. 1 is a perspective view of my improved pressing and rolling device;
- Fig. 2 is a plan view thereof;
- 25 Fig. 3 is a side elevation thereof;
- Fig. 4 is an end view, looking in the direction of the arrow 4 in Fig. 3;
- Fig. 5 is an enlarged sectional side elevation of the device;
- 30 Fig. 6 is a sectional side elevation of the removable casing or cylinder with a tie wound thereon;
- Fig. 7 is a side elevation of a clip or holding device;
- 35 Fig. 8 is a plan view thereof, and
- Fig. 9 is a view similar to Fig. 6 but showing the clip in use.

Referring to the drawings, my improved pressing and rolling device comprises a base 10 having a bracket 11 secured thereto and projecting upward therefrom. The bracket 11 is provided with a bearing portion 12 for a shaft 14. A cross bar 15 is secured to one end of the shaft 14 and is provided with knobs or handles 16 by which the shaft may be conveniently turned.

An elongated barrel 20 is mounted on the other end portion of the shaft 14, and the shaft 14, cross bar 15 and barrel 20 are manually rotatable as a unit. The barrel 20 is preferably provided with a longitudinal groove 22 for a purpose to be described.

A presser roll 25 is pivotally mounted in offset bearing portions 26 of a rocker plate 27 loosely secured to the base 10 by screws 28. By pressing

27, the roll 25 may be moved upward against the barrel 20 or a tie wound thereon.

A hollow casing or cylinder 40 is slidably mounted on the barrel 20 and is preferably provided with an inwardly projecting grooved rib 41 (Fig. 5) adapted to be received in the longitudinal groove 22 of the barrel 20. Relative rotation of the barrel and casing is thus prevented.

The casing or cylinder 40 also has an enlarged flange or head 44 at one end thereof, to which may be secured a wire spring 45 which is bent to extend longitudinally of the cylinder 40 and which is preferably normally located in the groove of the rib 41.

In the operation of my improved pressing or 15 rolling device, the cylinder 40 is placed on the barrel 20, and the end of a tie or ribbon, as T, is inserted under the wire spring 45 as shown in Fig. 1.

The operator then guides the tie with one hand, 20 which same hand also rests on the end portion 30 of the rocker plate 27 and presses the roll 25 firmly against the tie as it is wound on the cylinder 40. With his other hand, the operator grasps the handle 16 and slowly turns the barrel 20 and cylinder 25 40, all parts cooperating as shown in Fig. 5.

A tie or ribbon may thus be conveniently guided and smoothed as it is wound, and the winding operation is quickly and easily performed. A wound tie with varying widths in 30 different parts presents the sectional appearance indicated in Figs. 6 and 9.

Unwinding of the tie or ribbon may be prevented by securing the wound article in any convenient manner. I preferably provide a special spring clip 50 for this purpose. This clip has spaced attaching portions 51 which may be readily slipped over the end of the cylinder 40 as indicated in Fig. 9. By so doing, the spring portion of the clip is placed under tension and firmly 40 holds the tie or ribbon from unwinding.

The cylinder 40 with its wound and secured tie or ribbon may then be set aside until wanted, and the winding device is immediately available for further use. It will be understood that a 45 plurality of cylinders 40 will be furnished with each winding device, so that any number of ties or ribbons may be rolled and stored.

It has been found by use that a tie or ribbon thus smoothed and rolled and retained for a 50 few hours in rolled condition loses its wrinkles and quickly resumes its original freshness of appearance. Frequent ironing is thus effectually avoided.

Having thus described my invention and the 55

- advantages thereof, I do not wish to be limited to the details herein disclosed, otherwise than as set forth in the claims, but what I claim is:—
1. A tie pressing and rolling device comprising a base, a winding member rotatably mounted thereon, a cylinder removably mounted on said member, means to secure one end of a tie to said cylinder, manually operable means to turn said winding member, and means to smooth and press said tie during the rolling thereof on said cylinder.
  - 5 2. A tie pressing and rolling device comprising a base, a winding member rotatably mounted thereon, a cylinder removably mounted on said member, means to secure one end of a tie to said cylinder, manually operable means to turn said winding member, a pressing roller, and a support for said roller manually movable to press said roller against said tie as it is rolled on said cylinder.
  - 10 3. A tie pressing and rolling device comprising a base, a winding member rotatably mounted thereon, a cylinder removably mounted on said member, means to secure one end of a tie to said cylinder, manually operable means to turn said winding member, a pressing roller, and a rocking support for said roller manually operable to move said roller to operative position and to hold said roller yieldingly against said tie during the winding thereof.
  - 15 4. A tie pressing and rolling device comprising a base, a winding member rotatably mounted thereon, a cylinder removably mounted on said member, means to secure one end of a tie to said cylinder, manually operable means to turn said winding member, a pressing roller, and a rocking support for said roller, a portion of said support being positioned for engagement by the hand which holds and guides the tie and being movable thereby to operative position.
  - 20 5. A tie pressing and rolling device comprising a base, a winding member rotatably mounted thereon, a cylinder removably mounted on said member, means to secure one end of a tie to said

cylinder, manually operable means to turn said winding member, means to smooth and press said tie during the winding thereof on said cylinder, and means to retain the rolled tie on said cylinder.

6. A tie pressing and rolling device comprising a base, a winding member rotatably mounted thereon, a cylinder removably mounted on said member, means to secure one end of a tie to said cylinder, manually operable means to turn said winding member, and means to smooth and press said tie during the winding thereof on said cylinder, said cylinder having an enlarged head at one end on which head it may rest upright in storage position.

7. A tie pressing and rolling device comprising a base, a winding member rotatably mounted thereon, a cylinder removably mounted on said member, means to secure one end of a tie to said cylinder, manually operable means to turn said winding member, a pressing roll, and means to cause said roll to yieldingly engage a tie on said cylinder during the winding of said tie.

8. A tie pressing and rolling device comprising a base, a winding member rotatably mounted thereon, a cylinder removably mounted on said member, means to secure one end of a tie to said cylinder, manually operable means to turn said winding member, a pressing roll, and a rocking support for said roll having a portion extending under said member and projecting at the opposite side of said member and engageable by the hand holding and guiding the tie.

9. A tie pressing and rolling device comprising a base, a winding member rotatably mounted on said base and supported at one end only, a cylinder slidable on said member from the free end thereof, means to prevent relative rotation between said cylinder and member, means to turn said member and cylinder to wind a tie thereon, and means to press and smooth said tie as it is wound on said cylinder.

FRANK O. BERGSTRAND.
